(57) CLAIM

The ornamental design of a character sticker, as shown and described.

DESCRIPTION

The file of this patent contains at least one drawing executed in color. Copies of this patent with color drawing(s) will be provided by the Office upon request and payment of the necessary fee.

The FIGURE is a front view of a character sticker, showing my design.

The broken lines represent the boundaries of the claimed design and form no part of the claimed design.
